R. NARDI,
DOOR CHECK OR STOP,
APPLICATION FILED NOV. 29, 1918.

1,317,888.

Patented Oct. 7, 1919.

INVENTOR

Romolo Nardi
By W. W. Williamson
Atty.

UNITED STATES PATENT OFFICE.

ROMOLO NARDI, OF CAMDEN, NEW JERSEY.

DOOR CHECK OR STOP.

1,317,888.

Specification of Letters Patent.

Patented Oct. 7, 1919.

Application filed November 29, 1918. Serial No. 264,750.

To all whom it may concern:

Be it known that I, ROMOLO NARDI, a subject of the King of Italy, residing at Camden, in the county of Camden and State of New Jersey, have invented new and useful Improvements in Door Checks or Stops, of which the following is a specification:

My invention relates to new and useful improvements in a door check or stop, and has for its object to provide an exceedingly simple and effective device of this character which will hold a door in an open position in a positive manner, but which is so constructed that the parts may be readily actuated to permit the closing of the door.

A further object of the invention is to provide a door check or stop which may be readily applied to one of the surfaces of a door and to a wall, thus making it unnecessary to cut into the door or cut away any part of the door or wall.

Another object of the invention is to construct a door check or stop comprising a latch adapted to be fastened to some stationary object, as the wall of a building and to provide a catch for application to a suitable portion of a door or other similar hinged object whereby the latch will co-operate with the catch when the door is opened a sufficient distance, said catch being operated by a lever or handle, preferably located adjacent the door knob and connected with said catch by means of wire, a cable or an equivalent thereof.

A still further object of the invention is to provide holding means comprising a plate having a lug and provided with ears having a catch pivoted therebetween for co-operation with a suitable latch; an actuating means comprising a plate having a lug and carrying a stationary handle a pivoted operating lever; a tube connected with the lugs on said plates and a wire or other suitable connecting cable, one end of which is fastened to the catch and the other end to the operating lever, whereby said catch may be actuated in one direction.

With these ends in view, this invention consists in the details of construction and combination of elements hereinafter set forth and then specifically designated by the claim.

In order that those skilled in the art to which this invention appertains may understand how to make and use the same, I will describe its construction in detail, referring

by numerals to the accompanying drawing forming a part of this application, in which:

Figure 1, is a perspective view of a door with its jamb and surrounding wall illustrating the application of my door check or stop.

Fig. 2, is an enlarged front elevation of the parts which are applied to the door having the casing, coverings or housings removed from the plates and a portion of the tube being shown in section.

Fig. 3, is an edge view of the holding means or the plate carrying the catch, a portion of casing or housing being broken away and shown in section, and

Fig. 4, is an edge view of the latch.

In carrying out my invention as here embodied, 2 represents that which I term the holding means and comprises a plate 3 provided with holes 4 for the passage of suitable fastening devices, such as screws, so that said plate may be fastened to some suitable portion of a door and this plate carries a lug 5 preferably circular in cross section. In one end of said lug is formed a socket 6, while in the other end is formed a passage-way 7 communicating with the socket. Adjacent the end opposite said lug 5, the plate carries a pair of spaced ears 8 in which are journaled the trunnions 9 of the catch 10, the latter having a hole 11 for registration with the barb 12 of the latch 13, said latch being fastened to some stationary object such as the wall of a building.

The catch 10 is provided with a depending projection 14 which coacts with the plate 3 to limit the movement of the catch in one direction and said catch also carries a post 15 which is provided with a slot or notch for the reception of the loop 16 of the wire 17, said loop being held in place by a pin 18 which is driven into the post and passes through the loop. In forming the loop the wire is coiled about itself to provide or produce the enlargement 19. The wire 17 passes through the lug 5 and has a spring 20 coiled about it with one end of said spring engaging the lug 5, as the stationary member and the opposite end engaging the enlargement 19, as the movable element so that said wire and the members connected therewith will be normally forced in one direction.

The operating parts of the holding member are preferably inclosed as much as possible and in order to so inclose said parts I

provide a housing 21 of suitable thin, resilient metal so that one end will spring about the lug 5 to hold said end in place while the opposite end of said housing is provided with a hole for registration with the point of a fastening means or pin 22 carried by the plate 3. The housing has a portion thereof cutaway to form an opening through which a portion of the catch may project and into which passes the barb 12 of the latch 13, when the catch and latch are brought into coöperative positions, and this housing is so cut away in forming the opening that a tongue 23 is produced which is bent inward and registers with the opening 11 in the catch 10 when the latter is actuated.

The reference numeral 24 indicates what I term the actuating means and comprises a plate 25 having holes 26 for the passage of suitable fastening means, such as screws, whereby said plate may be attached to some suitable portion of the door, as for instance that portion adjacent the locality of the door knob, and this plate carries a lug 27 similar in all details to the lug 5. The plate 25 is also provided with a stationary handle 28 and an operating lever 29 is pivoted between said stationary handle and the plate, said lever being fulcrumed intermediate its ends on a pin or rivet 30, while to the inner end of said lever 29 is secured one end of the wire 17.

The holding means and the actuating means are joined together or connected by means of a tube 31 the ends of which are threaded or otherwise secured in the sockets of the lugs 5 and 27 and this tube incloses the wire 17 so that the latter is entirely hidden from view and housed to prevent outside interreference therewith.

The inner ends of the handle 28, the lever 29 and the end of the wire 17 which is attached to the lever, are suitably inclosed by a casing or housing 32 attached in any suitable and approved manner to the plate 25 as by rivets.

In practice the catch and its operating parts are attached to any suitable or convenient part of the door and the latch is secured to the wall or other stationary object in alinement with the catch 10, so that when the door is opened a sufficient distance the catch 10 will engage the beveled or arcuate face of the barb 12 and ride over it until the nose of said barb registers with the opening 11 in the catch 10 at which time the action of the spring 20 will force the catch 10 in back of the barb thus locking the door in an

open position and preventing its accidental closing.

When it is desired to close the door it is only necessary to take hold of the stationary handle 28 and the operating lever 29 with the forefinger and thumb so as to press the operating lever toward the stationary handle, which will move the catch 10 against the action to the spring 20, through the medium of the wire 17, to disengage the catch 10 from the latch. As soon as the pressure on the operating lever 29 is removed the spring 20 will return the catch 10 to its normal position until stopped by engagement of the projection 14 with the face of the plate 3.

Of course I do not wish to be limited to the exact details of construction as herein shown as these may be varied within the limits of the appended claim without departing from the spirit of my invention.

Having thus fully described my invention what I claim as new and useful is:—

A door check or stop, comprising in combination, a plate, a lug carried thereby, said lug having a socket therein projecting part way through the lug and provided with a pasageway through the balance of said lug and in communication with the socket, ears carried by the plate, a catch pivoted between said ears, said catch having an opening therein and provided with a depending projection acting as a stop and carrying a lug or post, a casing or housing attached to said plate, another plate, a lug carried by said other plate, said lug having a socket therein projecting part way therethrough and further provided with a pasageway projecting through the balance of the lug and communicating with the socket, a stationary handle carried by the last named plate, an operating lever pivoted between a portion of said handle and the plate carrying the same, a tube having its ends mounted in the sockets of the lugs of each plate, a wire passing through the lugs and said tube, one end of said wire being fastened to the actuating lever and the other end to the lug or post carried by the catch, a spring coiled about said wire and located between the catch and the lug on the plate with which said catch is connected for normally forcing said catch in one direction and a latch with which the catch is adapted to coöperate.

In testimony whereof, I have hereunto affixed my signature.

ROMOLO NARDI.
